UNITED STATES PATENT OFFICE.

HENRIETTA L. HAYNES, OF BOSTON, MASSACHUSETTS.

COIN-HOLDER.

SPECIFICATION forming part of Letters Patent No. 633,839, dated September 26, 1899.

Application filed January 20, 1899. Serial No. 702,840. (No model.)

To all whom it may concern:

Be it known that I, HENRIETTA L. HAYNES, a citizen of the United States, residing at Boston, in the county of Suffolk and State of Massachusetts, have invented certain Improvements in Coin-Holders, of which the following is a specification.

My invention has for its object to provide a neat and convenient pocket device for securely holding small coins in such manner as to permit of their ready withdrawal when required for use; and to this end my invention consists in a coin-holder composed of a channeled strip doubled to form two branches or bifurcations, between which the coins are held at their edges, combined with a self-adjusting locking device normally extending over the ends of the two branches of the holder to retain the coins in place and movable laterally to permit of their withdrawal for use, as hereinafter fully set forth.

In the accompanying drawings, Figure 1 is a perspective view of my improved coin-holder adapted for holding coins of two different denominations. Fig. 2 is an elevation of one side of the same, showing the manner in which the coins are held at their edges. Fig. 3 is an elevation of the opposite side of the holder. Fig. 4 is a top view of the same. Fig. 5 is a transverse section on the line 5 5 of Fig. 2.

In the said drawings, A represents my coin-holder, which is composed of a strip or piece of sheet metal provided with two parallel channels or grooves b c. This strip is doubled to form two branches or members d d, between which the coins are held at their edges which lie within the channels or grooves b c, as shown in Figs. 2 and 3. The larger coins—for instance, those of the five-cent denomination—are held within the oppositely-disposed portions of the channel b, and the smaller coins—for example, those of the ten-cent denomination—are held within the oppositely-disposed portions of the channel c, which lie nearer together than those of the channel b, both channels being of such width as to permit the coins to partially overlap each other, as shown in Figs. 2, 3, and 5, whereby the holder is adapted to contain a greater number of coins, each one of which being exposed in the space between the two branches

of the holder can be readily pushed along the channel by the thumb or finger and taken out of the holder when required for use. I prefer to have the two branches converge 55 slightly at their outer ends, leaving the inner portions sufficiently far apart to permit the coins to be pushed up to the outer end with a minimum amount of friction.

In order to prevent the accidental escape 60 and loss of the coins contained within the holder, I provide a self-adjusting yielding locking device B, which is preferably composed, as shown, of a piece of spring-wire bent double or into the form of a bail and 65 having the ends of its side portions 10 10 soldered or otherwise fastened at 12 12 to the outer sides of the two branches d d. The upper or outer portion of the wire which extends over the ends of the branches d d and across 70 the space between the same is bent into serpentine shape, forming three lips or guards 16 18 18, the central one, 16, lying in the path of the smaller coins in the channel c, and those, 18, lying in the path of the larger coins 75 in the channel b, thereby preventing the withdrawal of the coins from the holder until they have been moved out of the way by pushing the guard to one side or the other with the finger, according as it may be desired to withdraw the larger or smaller coins, the resiliency of the wire causing the locking device when released to immediately resume its normal position over the coins and close the end of the holder, as required. This locking device 80 also serves to stiffen the holder and prevents the spreading apart of the two branches d d.

If desired, both of the channels of the holder may be adapted for holding coins of the same 90 denomination, or the holder may be constructed with a single channel only for holding coins of but one denomination.

What I claim as my invention, and desire to secure by Letters Patent, is—

1. A coin-holder consisting of a channeled strip doubled to form two branches or bifurcations between which the coins are held at their edges, combined with a self-adjusting locking device normally extending over the 100 ends of the two branches of the holder, to retain the coins within the same, said locking

device being movable to permit of the withdrawal of the coins for use, substantially as described.

2. A coin-holder consisting of a channeled strip doubled to form two branches or bifurcations between which the coins are held at their edges, combined with a self-adjusting bail - shaped locking device composed of spring-wire, and having its ends secured to the sides of the holder, and its upper or outer portion bent to form overhanging lips or guards

adapted to retain the coins within the holder, said locking device being movable laterally to permit of the withdrawal of the coins for use, substantially as described. 15

Witness my hand this 13th day of January, A. D. 1899.

HENRIETTA L. HAYNES.

In presence of—

P. E. TESCHEMACHER,
M. B. WILSON.
